UNITED STATES PATENT OFFICE.

WILLIAM WATTIE, OF WORCESTER, MASSACHUSETTS, ASSIGNOR TO THE CROMPTON & KNOWLES LOOM WORKS, OF SAME PLACE.

MULTIPLIER MECHANISM FOR LOOMS.

SPECIFICATION forming part of Letters Patent No. 585,607, dated June 29, 1897.

Application filed June 1, 1896. Serial No. 593,756. (No model.)

To all whom it may concern:

Be it known that I, WILLIAM WATTIE, a citizen of the United States, residing at Worcester, in the county of Worcester and State of Massachusetts, have invented certain new and useful Improvements in Multiplier Mechanism for Looms, of which the following is a specification.

My invention relates to looms for weaving textile fabrics and to that class of looms provided with an auxiliary or multiplier pattern chain or surface in addition to the main pattern chain or surface.

By means of the multiplier pattern-chain certain bars of the main pattern-chain of the drop-box-indicating mechanism may be repeated without constructing successive similar bars in said main chain, as is well understood.

The object of my present invention is to provide, in addition to the multiplier pattern-chain and the main pattern-chain of the drop-box-indicating mechanism above described, a third pattern chain or surface, which I term a "supplemental" chain, by means of which I can weave stripes in the body of the goods without increasing the number of bars in the main pattern-chain or increasing the length thereof over what is used in weaving plain body goods. Said third pattern-chain is connected directly with and operates the shuttle-drop-box-shifting mechanism.

Heretofore in weaving the class of goods above referred to the main pattern-chain has to be provided with additional bars for weaving in the stripes through the body of the goods between the headings, thus increasing very much the length of the chain, for one revolution of the whole chain will be necessary to complete the whole pattern. For example, in weaving a blanket six feet in length there will be two thousand four hundred and forty-eight picks. If only one pattern-chain is used, this chain must have two thousand four hundred and forty-eight bars, but by the use of a second pattern-chain (the ordinary multiplier pattern-chain above referred to with eight bars of chain) the number of bars in the main pattern-chain may be reduced to three hundred and thirty-eight to weave a blanket with the ordinary headings and fifty-six stripes through the body thereof between the headings.

Now by the use of my third or supplemental chain with sixteen bars, which is used to weave the striped body of the blanket between the headings, the number of bars in the main pattern-chain can be reduced to forty-seven, making a total of sixty-three bars of chain in the two pattern-chains, the main chain, and my third or supplemental chain, as against three hundred and thirty-eight bars in the main pattern-chain when my supplemental pattern-chain is not used. The number of bars of pattern-chain in the second or multiplier pattern-chain is the same in each case, (eight bars.)

My invention consists in certain novel features of construction and operation of the pattern-chain mechanisms, of the drop-box-indicating mechanism of looms of the class above described, and more particularly in combining with the main pattern chain or surface and the multiplier pattern chain or surface and the shuttle-drop-box-shifting mechanism a third pattern chain or surface and providing mechanism for operating said third pattern-chain in connection with the main and multiplier pattern-chains and the shuttle-drop-box-shifting mechanism, for the purpose above stated.

I have shown in the drawings my improvements applied to a four-by-one box-loom, and combined with main and multiplier pattern-chain mechanisms and operating parts, of substantially the same construction and operation as is shown and described in United States Letters Patent No. 544,356, of August 13, 1895, and also in my pending application for United States Letters Patent, Serial No. 579,137, to which reference is hereby made.

Referring to the drawings, Figure 1 shows a loom side upon the upper part of which is supported the box-pattern-indicating mechanism embodying my improvements and upon the lower part the box-shifting mechanism. Fig. 2 is a front view of the box-pattern-indicating mechanism shown in Fig. 1 and looking in the direction of arrow *a*, Fig. 4. Fig. 3 is a rear view of the box-pattern-indicating mechanism, looking in the direction of arrow *b*, Fig. 4. Fig. 4 is a plan view looking in the direction of arrow *c*, Fig. 2. Fig. 5 is a vertical cross-section on line 5-5, Fig. 4, looking in the direction of arrow *a*, same figure. Fig. 6 is a vertical cross-section

tion on line 6 6, Fig. 4, looking in the direction of arrow *a*, same figure. Fig. 6^a corresponds to Fig. 6, but shows some of the parts in a different position. Fig. 7 is a detail of 5 the indicating-disk on the friction-take-up roll and the engaging finger or lever, looking in the direction of arrow *d*, Fig. 8. Fig. 8 is a plan view of the parts shown in Fig. 7, looking in the direction of arrow *e*, same figure; 10 and Fig. 9 is a perspective view of one of the adjustable indicating cams or switches on the indicating-disk. Figs. 2 to 9, inclusive, are shown on an enlarged scale.

In the accompanying drawings, 1 is the 15 loom-arch stand, on the upper part of which is secured the stand or frame 2, on which are supported the several parts of the drop-box-pattern-indicating mechanism. The drop-box-pattern-indicating mechanism is in this 20 instance, as above stated, for a four-by-one box-loom, and is of substantially the same construction and operation as the drop-box-pattern-indicating mechanism shown in said Patent No. 544,356 and in my said pending 25 application, Serial No. 579,137, with my present improvements combined therewith. In said pattern-indicating mechanism 3 is the main-pattern-chain cylinder, loosely mounted on a stud 4, secured in the frame 2. Said 30 cylinder or barrel 3 is of the ordinary construction, having grooved or notched heads or ends, and carrying the main pattern-chain 5, made up of links 6, which connect the bars 7, upon which are mounted tubes 8 and rolls 9 35 in the ordinary way. The cylinder 3 is provided with a hand-wheel 10, by means of which said cylinder is turned in either direction, as desired.

The auxiliary or multiplier pattern-chain 40 cylinder 11 is loosely mounted on a stud 12, supported in the frame 2 and in the bracket 2', and in this instance upon the opposite side of the stand 2 from the main-pattern-chain cylinder. (See Fig. 4.)

45 The cylinder 11 carries the auxiliary or multiplier pattern-chain 13, made up of links 6, bars 7, tubes 8, and rolls 9, similar to the main pattern-chain 5. The cylinder 11 is provided with a hand-wheel 14 to turn said 50 cylinder as desired.

On a stud 15, secured in a boss 16 on one end of the stand 2, are loosely mounted the outer weighted ends of two shuttle-box-indicator levers 17 and 18, which extend over 55 and are operated by the main pattern-chain 5. The inner ends of the levers 17 and 18 are in this instance provided with open-end slots to receive the loops or heads 19' on the upper ends of the connector-rods 19, (see 60 Figs. 1 and 2,) which lead to the two connectors 48, to which they are adjustably attached by a collar 49 and set-screw 50. (See Fig. 1.) The connector-rods 19 can move up without raising the levers 17 and 18.

65 The connectors 48, to be hereinafter described, are attached at their lower ends to the vibrator-levers 20 of the box-shifting

mechanism shown in Fig. 1, and which may be of the ordinary construction and operation, and consists of the upper and lower cylinder-gears 21 and 22, vibrator-gear 23, carried on the vibrator-lever 20, pivoted at its outer end at 24, and the vibrator-connector 25, pivoted at one end on the vibrator-gear 23 and connected at its other end to the compound lever 26, which operates the shuttlebox-lifter rod 27, all in the usual way, and shown and described more particularly in United States Patent No. 551,104, of December 10, 1895.

A ratchet-wheel 28 is mounted on the stud 4, and is secured to the main-pattern-chain cylinder 3. (See Fig. 4.) A stop-wheel 29 is also mounted on the stud 4 and secured to the ratchet-wheel 28 to turn with said ratchet-wheel. Said stop-wheel is provided with concave portions 29' in its periphery, into which is adapted to extend the convex portion 30' on the lock-lever 30, pivoted at 31 on the frame 2, (see Fig. 5,) and connected by 35 a spring 32 and link 32' to a similar lock-lever to be hereinafter described.

On the stud 12 of the multiplier-pattern-chain cylinder 11 is mounted a ratchet-wheel 33, (see Figs. 4 and 6,) which is secured to 40 the multiplier-pattern-chain cylinder 11. A stop-wheel 34, Fig. 4, is also mounted on said stud 12, and is secured to the ratchet-wheel 33 to turn with said ratchet-wheel, and is provided with concave portions 34' in its periphery, into which extends a convex portion 35' on the lock-lever 35, pivoted at 35' on the frame 2. (See Figs. 3, 4, and 5.)

A spring 36, encircling a pin 36', sliding at one end in an eye 36'', and secured at its 45 other end to the lock-lever 35, (see Fig. 3,) acts to hold said lever 35 in engagement with the stop-wheel 34.

I will now describe my third or supplemental pattern chain or surface, combined 50 with the main pattern-chain and the multiplier pattern-chain, above described, and the shuttle-drop-box-shifting mechanism, and in this instance located at the front of the stand or frame 2 at the opposite end thereof from 55 the main pattern-chain 5. (See Fig. 4.)

On a stud 37, supported in the frame 2 and the bracket 2'', is loosely mounted a pattern-chain cylinder 38, carrying the supplemental pattern-chain 39, made up of links 6, bars 7, 60 tubes 8, and rolls 9 in the ordinary way. A hand-wheel 40 is secured to the pattern-chain cylinder 38 to turn the pattern-chain, as desired.

On the stud 37 of the supplemental chain 65 39 is mounted a ratchet-wheel 41, which is secured to the supplemental-pattern-chain cylinder 38. A stop-wheel 42 is also mounted on said stud 37 and is secured to the ratchet-wheel 41 to turn with said ratchet-wheel and is provided with concave portions 42' in its periphery, into which is adapted to extend a convex portion 43' on the lock-lever 43, pivoted at 43'' on the frame 2 (see Fig. 5) and

connected by a rod 32' and a spring 32 to the lock-lever 35. The spring 32 acts to draw the lock-levers 30 and 43 toward each other to hold them in engagement with the stop-wheels 29 and 42, as shown in Fig. 5.

On a stud 44, secured in a boss 45 on the end of the frame 2, are loosely mounted the weighted outer ends of two shuttle-box-indicator levers 46 and 47, which extend over and are operated by the supplemental pattern-chain 39. The inner ends of the levers 46 and 47 are in this instance provided with open-end slots to receive the loops or heads 48' on the upper end of the connector-rods 48 to allow said rods to move up without raising said levers. The lower ends of said rods 48 are attached to the vibrator-levers 20 of the box-shifting mechanism, as above described.

It will be seen that the movement of the indicator-levers 17 and 18 on the main pattern-chain 5 through the connector-rods 19, attached to the connector-rods 48, will communicate motion to the vibrator-levers 20 of the box-shifting mechanism, and the indicator-levers 46 and 47 on the supplemental pattern-chain 39, through the connector-rods 48, attached to the vibrator-levers 20, will also communicate motion to said vibrator-levers 20 to operate the box-shifting mechanism.

I will now describe the mechanism for operating the main pattern-chain 5, the multiplier pattern-chain 13, and the supplemental pattern-chain 39. Said mechanism corresponds to the mechanism shown and described in said Patent No. 544,356 and in my said application, Serial No. 579,137, but is adapted to operate three chains instead of two.

In the lower central part of the frame 2 in a boss 51 is mounted a shaft 52, (see Figs. 4 and 5,) adapted to have a rocking motion. On the front end of the shaft 52 is secured by a set-screw 53 the lower end of the rocking pawl-carrying arm 54. Upon the upper end of said pawl-carrying arm 54 are pivoted three pawls 55, 56, and 57. The pawl 55 acts as a pull-pawl and is provided with a hook 55' at its free end, which extends over and engages the teeth on the ratchet-wheel 41 to move said ratchet-wheel and with it the supplemental-pattern-chain cylinder 38 and chain 39. The pawl 56 is pivoted on the opposite side of the pawl-carrying arm 54 from the pawl 55 and acts as a push-pawl, and its free end engages the teeth on the ratchet-wheel 33 to move said ratchet-wheel and with it the multiplier-pattern-chain cylinder 11 and chain 13. The pawl 57 is pivoted in this instance on the front of the pawl-carrying arm 54 and extends in an opposite direction to the pawls 55 and 56. Said pawl 57 acts as a push-pawl, and the free end thereof engages with the ratchet-teeth on the ratchet-wheel 28 to move said ratchet-wheel and the main-pattern-chain cylinder 3 and chain 5.

Upon the opposite end of the shaft 52 from the pawl-carrying arm 54 is secured the inner

end of the arm 58, (see Fig. 3,) which is connected through a give-way or lock connection with the driven part of the loom. Said lock connection and mechanism connected with the stop-motion shaft to automatically operate said lock connection and disconnect the arm 58 to stop the movement of said arm and the pawl-carrying arm 54, so that the movement of the pattern-chains will cease in case the filling gives out and the filling stop-motion shaft acts to stop the loom, is of the same construction and operation as shown and described in said Patent No. 544,336, to which reference is hereby made for a detail description of the construction and operation of said mechanism. I will briefly describe said mechanism herein.

The outer end of the arm 58 is provided with a screw or pin 59, which is adapted to engage a notch 60", leading out from a vertical slot 60' in the head 60 on the upper end of a connector-rod 61. The lower end of said rod 61 is connected with a cam on the bottom shaft or with some other driven part of the loom, (not shown,) from which a continuous up-and-down motion is communicated to said rod 61 and, through the arm 58, to the rock-shaft 52 and the pawl-carrying arm 54.

From the head 60 of the connector-rod 61 a connection 62 leads over a pulley 63, loose on the shaft 52, and over two pulleys 64 and 65, mounted on the loom side, (see broken lines, Fig. 1,) to an arm 66, fast on the stop-motion shaft 67, so that when the loom is stopped by the stop-motion shaft in case the filling gives out the connection 62 will be pulled to draw the head 60 of the connector-rod 61 to the right in Fig. 3 and move the pin 59 out of the notch 60" into the slot 60' to allow the head 60 and connector-rod 61 to move up and down without moving the arm 58, so that the pattern-indicating mechanism will be instantly stopped though the loom may continue to run.

A pawl 68, pivoted at 69 on the arm 58 and bearing at one end against the inner edge of the head 60 and attached at its other end to one end of a spring 70, secured at its other end to the arm 58, acts to hold the pin 59 in the notch 60" in the head 60 to form a lock connection between the connector-rod 61 and the arm 58.

I will now describe the mechanism for controlling the engagement of the pawls 55, 56, and 57 with their respective ratchet-wheels, so that only one pattern-chain will be operated at a time, and each chain—that is, the main pattern-chain, the multiplier pattern-chain, and the supplemental pattern-chain—will be operated at the proper time.

The stopping and starting of the chains at the proper time are controlled by indicator-levers extending over and operated by the pattern-chains and connecting mechanisms. As before stated, the main pattern-chain 5 is used to weave in the headings or borders and the multiplier pattern-chain 13 is used, in

connection with the main pattern-chain, to repeat certain bars of the main pattern-chain, the main pattern-chain being at rest while the multiplier pattern-chain is working and 5 the multiplier pattern-chain being at rest while the main pattern-chain is working.

By means of the third or supplemental pattern-chain 39 the striped body of the fabric between the headings is woven, and when 10 said third chain is working the other two chains are at rest.

In order to control the movement of the ratchet-wheel 33 of the multiplier-pattern-chain mechanism, I provide a shield or guard 15 71, which extends under the pawl 56, (see Fig. 4,) to raise said pawl and prevent its engagement with said ratchet-wheel 33. The shield or guard 71 is pivoted at 72 on the stand 2, (see Fig. 6,) and has an extension or arm 71' 20 on the opposite side of its pivot-support, the end of which is provided with an open-end slot, into which extends a pin 73, extending out from the weighted end 74' of the indicator-lever 74, extending over the main pattern-chain 5 and loosely mounted at its outer 25 end on the stud 15. (See Fig. 4.) It will thus be seen that the row of indicators on the main pattern-chain 5 under the indicator-lever 74, through said lever 74, pin 73, and the arm 71' 30 and shield 71, controls the action of the pawl 56 of the multiplier-pattern-chain mechanism.

A shield or guard 75 extends under the pawl 57, which moves the ratchet-wheel 28 of the main-pattern-chain mechanism. The shield 35 75 is pivoted at 76 on the stand 2, (see Fig. 6,) and has an arm or extension 75' on the opposite side of its pivot-support, the end of which is provided with an open-end slot, into which extends a pin 77, extending out from the 40 weighted end 78' of the indicator-lever 78, extending over the multiplier pattern-chain 13 and loosely mounted at its outer end on the stud 44. (See Figs. 4 and 6.) It will thus be seen that the row of indicators on the multiplier pattern-chain 13 under the indicator-lever 78, through said lever 78, pin 77, and the arm 75' and shield 75, controls the action 45 of the pawl 57 of the main-pattern-chain mechanism, in connection with a shield or guard 50 79, to be hereinafter described, connected with the supplemental-pattern-chain mechanism.

I will now describe the construction and operation of the shield or guard which extends 55 under the pawl 55, which operates the ratchet-wheel 41 of the supplemental pattern-chain 39.

The shield or guard 80 is pivoted at 81 on the stand 2. (See Fig. 6.) Said shield or 60 65 guard extends under the operating-pawl 55 of the supplemental pattern-chain 39. (See Fig. 4.) Upon the opposite side of the pivot 81 of the shield 80 is an extension or arm 82, upon the outer upper end of which is pivoted the lower end of the shield or guard 79, which 70 75 extends under the pawl 57 of the main-pat-

tern-chain mechanism and operates in connection with the shield 75, as above stated.

The shield 79 has a pivotal motion in a vertical plane on the supporting-arm 82 and is 70 provided with a rear extension 79', which engages an upward extension 82' on the arm 82. A spring 83, attached to the shield 79 and to the upward extension 82', (see Fig. 3,) holds the shield 79 in its raised position with the 75 rear extension 79' engaging the upward extension 82'.

Extending over the main pattern-chain 5 is an indicator-lever 84, the outer end of which is mounted loosely on the stud 15 and 80 the inner end provided with a pin 85, which extends over the top of the pawl-carrying arm 54 (see Fig. 4) to limit the downward motion of said lever. The indicator-lever 84 has a downward extension 84' thereon, (see 85 Fig. 3,) which is adapted to be engaged by an indicator 86 on the main pattern-chain.

The indicators which act on the indicator-lever 84 form a separate row of tubes and rolls between the heads or ends of the pattern-cylinder, or, as in this instance, the indicators may be substituted for one of the tubes which extend into the notches or grooves in the ends of the cylinder or barrel. (See Fig. 4.)

95 A link 87 connects the outer end of the indicator-lever 84 with the arm 82, forming a part of the shield 80. (See Figs. 2 and 3.)

An angle-lever 88 (see Figs. 5 and 6) is pivoted at 89 on the frame 2 and is provided with a notched portion 88' in the upper end of its vertical arm, into which a downward extension 82" on the arm 82 is adapted to extend. A spring 90, attached to the arm 82 and to the stand 2, and a spring 91, attached 105 to the angle-lever 88 and to the stand 2, act to hold the arm 82 and the angle-lever 88 in engagement, as shown in said Figs. 5 and 6.

Upon the stud 44 is loosely mounted the outer end of the indicator-lever 92, (see Figs. 110 2 and 4,) which extends over and is acted on by indicators on the supplemental pattern-chain 39. On the inner end of the indicator-lever 92 is hung the upper end of a lever 93, which has a vertical slot 93' in the lower part 115 thereof, with a notch 93" leading out from said slot. A spring 94 is secured at one end to the lever 92 and at its other end to the stand 2, and tends to keep the arm toward the right in Fig. 2.

To the lower end of the lever 93 is secured one end of a connection 95, which leads over a pulley 96, mounted in a hanger 97 on the stand 2 and over a second pulley 98 (shown by broken lines in Fig. 1) to the upper end of 120 the lever 99 of the indicating mechanism (shown in Figs. 7 and 8) and which is of the same construction and operation as shown and described in my said pending application, Serial No. 579,137. In said indicating mechanism the lever 99 is pivoted at its lower end on a stud 100, secured in the stand 101, and is 125 130

provided with a lever or indicating-finger 102, pivoted thereon to move in a horizontal plane, and the free end of the finger 102 is adapted to travel on the periphery of a disk 103, which 5 is the indicating-disk and in this instance is made integral with the gear 104, fast on the shaft 105 on the friction take-up roll. A pinion 106, fast on a driven shaft 107, meshes with the teeth on the gear 104. (See Fig. 7.) 10 A spring 108 is attached at one end to a rearward projection 102' on the finger 102 and at its other end to an extension 99' on the lever 99 (see Fig. 8) and acts to hold the rearward projection 102' in engagement with the 15 extension 99' on the lever 99 (see Fig. 8) and the free end of the finger 102 on the periphery of the disk 103.

On the indicating-disk 103 are secured, in 20 this instance by screws 109, adjustable indicating devices or switch-cams 110, in this instance two in number. As the indicating-disk 103 revolves, the indicating lever or finger 102 travels on the periphery thereof until it engages the curved plate 110' of the 25 switch-cam 110, which extends over the periphery of the disk, as shown in Fig. 9.

The curved plate 110' causes the finger 102 to leave the periphery of the disk 103 against the action of the spring 108, and the spring 30 111, secured at one end to the stand 101 and at its other end to the lever 99, acts to move the lever 99 on its pivot-stud 100 and cause the free end of the finger 102 to drop into the notch 110" in the switch-cam 110. The movement of the lever 99 through the connection 35 95 moves the lever 93, hung on the indicator-lever 92, to the left (see Fig. 2) and allows the screw or pin 112, which extends loosely through the slot 93' in said lever 93 and is 40 secured in the end of the angle-lever 88, as above described, to enter the notch 93", leading out from the slot 93', when a tube on the supplemental pattern-chain 39 comes under the indicator-lever 92 and allows said lever 45 and the lever 93 to drop down.

In the revolution of the supplemental pattern-chain 39 when a roll 9 comes under the indicator-lever 92 said lever will be raised and with it the lever 93, causing the angle-lever 88 by the engagement of the pin 112 thereon with the notch 93" to move on its pivotal support 89 and be disengaged from the arm 82 of the shield 80 (see Fig. 6^a) and allow the spring 90 to act to draw down the arm 82 50 and with it the shield 79, so that the pawl 57 can engage with the ratchet-wheel 28 of the main-pattern-chain mechanism. At the same time the shield 80 is raised to hold the pawl 55 out of engagement with the ratchet-wheel 55 60 41 of the supplemental-pattern-chain mechanism, and the continued revolution of the indicating-disk 103 causes the indicating-finger 102 to pass out of the notch 110" in the switch-cam 110 onto the periphery of the indicating-disk 103, moved by the spring 108, and acts to move back the lever 99 against the action of the spring 111 and loosen the

connection 95 to allow the spring 94 to act to draw the lever 93 to the right in Fig. 2 and disengage the pin 85 from the notch 93" and move it into the slot 93' to allow the lever 93 and the indicator-lever 92 to move freely up and down without moving the angle-lever 88. 70

The revolution of the main pattern-chain 5 brings the indicator 86 on said chain under 75 the indicator-lever 84 at the proper time and raises said lever 84 and through the link 87 raises the arm 82 and allows the spring 91 to act to draw over the angle-lever 88 and bring the end thereof under the arm 82 to hold it 80 in its raised position, as shown in Fig. 6.

The raising of the arm 82 raises the shield 79 under the pawl 57 of the main-pattern-chain mechanism and lowers the shield 80 under the pawl 55 of the supplemental-pattern-chain mechanism, as shown in Fig. 6. The shield 79, extending under the pawl 57 of the main-pattern-chain mechanism, is pivoted to the arm 82 to have a movement in a vertical plane independent of said arm, so 90 that the arm 82 may be raised while the pawl 57 is in engagement with the teeth of the ratchet-wheel 28, and after the pawl 57 has completed its stroke the spring 83 will then act to carry the pawl from engagement with 95 the ratchet-wheel by causing the shield 79 to lift the said pawl.

From the above description, in connection with the drawings, the operation of my improvements in box-indicating mechanism will 100 be readily understood by those skilled in the art and briefly is as follows: Suppose the several parts of the mechanisms to be in the positions shown in the drawings (Fig. 6^a showing the proper position of the pawl-shield 105 mechanism) and the loom running. The main pattern-chain 5 will be in operation through the pawl 57 operating the ratchet-wheel 28, (see Fig. 4,) and the heading or border of the blanket will be woven in case a blanket is 110 being woven. When a roll 9 comes under the indicator-lever 74, said lever is raised and through pin 73 raises the end 71' of the shield 71 and lowers said shield 71, allowing the pawl 56 to engage and turn the ratchet-wheel 33 and revolve the multiplier-pattern-chain cylinder 11 and the multiplier pattern-chain 13. The revolution of the chain 13 carries the roll 9 from under the indicator-lever 78, (see Fig. 4,) which drops down and through 120 pin 77 (see Fig. 6) lowers the end 75' of the shield 75 and raises the shield 75 to hold the pawl 57 out of engagement with the ratchet-wheel 28, so that the main pattern-chain 5 will stop. The multiplier pattern-chain 13 will continue to run until the indicator-lever 78 is raised by a roll 9, when the shield 75 will be lowered, and the main pattern-chain 5 will be operated, and the multiplier-chain 130 stop, and so on, the main and multiplier pattern-chains starting and stopping according to the indications of the pattern-surfaces and the drop-box mechanism being operated through levers 17 and 18. During this time

the third or supplemental pattern-chain is at rest. When in the revolution of the main pattern-chain 5 the indicator 86 (see Fig. 3) engages the projection 84' on the indicator-lever 84, said lever is raised and through link 87 raises the arm 82 of the shield 80, and with said arm 82 the shield 79 to hold the pawl 57 out of engagement with the ratchet-wheel 28 of the main pattern-chain 5 and stop said 5 chain. The raising of the arm 82 from the position shown in Fig. 6^a to the position shown in Fig. 6 lowers the shield 80 and allows the pawl 55 to engage and turn the ratchet-wheel 41 and the supplemental pattern-chain 10 15 39 at the same time the shield 79 is raised, as shown in Fig. 6, to stop the main pattern-chain 5. The revolution of the chain 39 brings a tube under the indicator-lever 92 (see Fig. 4) and lowers said lever and with it 20 the lever 93, bringing the notch 93" in the slot 93' opposite the pin 112 in the angle-lever 88. (See Fig. 2.) The supplemental pattern-chain 39 continues to run, weaving the striped body between the headings, in the 25 case of a blanket, until the revolution of the indicator-disk 103 on the take-up roll brings the cam-switch 110 in engagement with the lever 102. The lever 99 is then moved by the spring 111, and, through the connector 95, 30 (see Fig. 7,) the lever 93 is moved to the left, (see Fig. 2,) so that the pin 112 will enter the notch 93", and the raising of the lever 93 through the indicator-lever 92 when a roll 35 comes under said lever will rock the angle-lever 88 and disengage the upright arm thereof from the arm 82, (see Fig. 6^a), causing the shield 79 to drop and allow the pawl 57 to put into operation the main pattern-chain 5. The shield 80 will at the same time be raised 40 to disengage the pawl 55 and stop the supplemental pattern-chain 39. As soon as the lever 102 of the indicating mechanism passes onto the periphery of the disk 103 the connector 95 will be released and the spring 94 act 45 to draw the lever 93 to the right in Fig. 2, so that the pin 112 will work free in the slot 93'. The supplemental chain 39 will remain at rest until the revolution of the main pattern-chain 5 brings the indicator 86 into position to operate the indicator-lever 84, when the operation above described will be repeated to start the supplemental chain 39. In this way the headings or borders are woven by the main and multiplier pattern-chains and the striped 50 55 body between the headings by the third or supplemental pattern-chain in weaving blankets or shawls, &c.

It will be understood that the details of construction of my mechanisms may be varied, if desired.

Having thus described my invention, what I claim as new, and desire to secure by Letters Patent, is—

1. In a loom provided with main-pattern-chain mechanism, and multiplier-pattern-chain mechanism, the combination with the

main-pattern-chain mechanism, and the multiplier-pattern-chain mechanism, and intermediate connecting mechanism, and mechanism for operating said pattern-chain mechanisms, of a third or supplemental pattern-chain mechanism, and intermediate mechanism connecting said supplemental-pattern-chain mechanism with the main-pattern-chain mechanism, and mechanism for operating said supplemental-pattern-chain mechanism, and connections from the cloth-take-up roll to an indicator-lever of the supplemental-pattern-chain mechanism, to automatically put into action the main pattern-chain, substantially as described. 70 75 80

2. In a loom of the class described, the combination with a main-pattern-chain mechanism, a multiplier-pattern-chain mechanism, and a third or supplemental-pattern-chain mechanism, of connections between the main and multiplier pattern-chain mechanisms, and between the main and supplemental pattern-chain mechanisms, and connections from the cloth-take-up roll to a supplemental indicator-lever of the supplemental-pattern-chain mechanism, and connections from said supplemental indicator-lever to the pawl shield or guard of the main-pattern-chain mechanism, to automatically operate said shield and put into action the main-pattern-chain mechanism from the supplemental-pattern-chain mechanism, substantially as described. 85 90 95

3. In a loom of the class described, the combination with the main-pattern-chain mechanism, and the multiplier-pattern-chain mechanism, and intermediate connecting mechanism, and mechanism for operating said two pattern-chain mechanisms, of a third or supplemental pattern-chain mechanism, and intermediate mechanism, connecting said supplemental-pattern-chain mechanism with the main and multiplier pattern-chain mechanisms, and mechanism for operating said supplemental-pattern-chain mechanism, substantially as described. 100 105 110

4. In a loom, the combination with a main-pattern-chain mechanism, a multiplier-pattern-chain mechanism, and a shuttle-drop-box-shifting mechanism, and connections between the main-pattern-chain mechanism and the box-shifting mechanism, to operate said shifting mechanism from the main pattern-chain, of a third or supplemental pattern-chain mechanism, and connections between said supplemental-pattern-chain mechanism and the drop-box-shifting mechanism, to operate said box-shifting mechanism from the supplemental pattern-chain and connections between the main-pattern-chain mechanism and the supplemental-pattern-chain mechanism substantially as set forth. 115 120 125
